UNITED STATES PATENT OFFICE.

ALEXANDER W. DREYFOOS, OF MOUNT VERNON, NEW YORK.

PHOTOGRAPHIC-PRINTING APPARATUS.

1,051,567.

Specification of Letters Patent. Patented Jan. 28, 1913.

Application filed February 9, 1911. Serial No. 607,463.

To all whom it may concern:

- Be it known that I, ALEXANDER W. DREYFOOS, a citizen of the United States, and a resident of Mount Vernon, in the county of Westchester, State of New York, have invented certain new and useful Improvements in Photographic-Printing Apparatus, of which the following is a full, clear, and exact specification.
- 10 My invention relates to improvements in apparatus for photographic printing by artificial light, and consists in the construction and arrangement of parts hereinafter described and pointed out in the claims.
- 15 The objects of my invention are to provide an apparatus of the character mentioned with a revoluble shutter, means for adjusting the shutter, and means for automatically controlling the rotation thereof whereby a proper regulation of the printing exposure and distribution of the light may be obtained.
- 20 In printing multiple copies from a negative or other printing element, or in making further reproductions of an old print, it is necessary, in order that the prints be uniform and alike in appearance, that the printing exposure, the distribution and the intensity of the light, be substantially the same for each copy printed.
- 25 By means of the nicety of regulation and the standardization afforded by my invention, I am enabled to accomplish the objects specified, as well as others not hereinbefore enumerated.
- 30 In the accompanying drawings, forming part of this specification Figure 1 is a plan view of my apparatus, partially in section and partially broken; Fig. 2 is a central transverse section in elevation; Fig. 3 is an end view in elevation, partly in section, along the line *a*—*a* in Fig. 1, showing the controlling mechanism; Fig. 4 is a view in elevation, looking from the front, showing an end of the shutter and the controlling mechanism; Fig. 5 is a plan view in detail of the switch; and Fig. 6 is a detail view of the engaging pin shown in Fig. 1.
- 35 Similar characters refer to similar parts throughout the several views.
- Having reference to the drawings, (1) denotes the housing of the apparatus the top part of which is arranged to form a printing frame; (2) a cover hinged (at 3) to the frame portion and having an attached spring (4) and a handle lever (5) whereby the cover may be raised or lowered. When the cover is lowered the handle lever and spring serve to press it against the negative and sensitized element so as to hold them firmly in place on the transparent bed plate (6). A suitable source of artificial light (7) is located within the housing below the printing frame. Between the light and the plate may be interposed, if desired, one or more thicknesses or plates (8) of a suitable translucent material to diffuse the light. In my apparatus I prefer to use an electric vacuum tube lamp (7) longitudinally supported near its ends on blocks (9) and provided with a suitable reflector (10) arranged to throw the light upward on the plate. Fastened to the housing, above the vacuum tube and parallel thereto, are a pair of opaque screens (11) spaced apart to form an aperture through which the light may pass. This aperture is arranged to be closed by a rotary shutter, as will be hereinafter explained. The screens have overhanging aprons (12) which are bent to conform to the curvature of the circumference of the rotary shutter and serve to prevent a leakage of light when the opening in the shutter is below the planes of the screens. I prefer to make the screens of any suitable material which may be easily bent in form, and to reinforce them with the ribs or angle irons (13). The screens are arranged for lateral adjustment by means of the fixed screws (14) acting on the movable nuts (15) carried thereon.
- 40 The rotary shutter is disposed axially about the vacuum tube. It consists of a hollow cylinder or drum (16) made of any suitable opaque material, having a section of its circumference removed to form an opening for the emission of light. This opening is approximately equal in length to the length of the bed plate, and in width, substantially equal to the distance between the overhanging edges of the screens (11). This cylinder is revolvably borne, near each end, on a series of roller bearings (17) suitably fastened in the upright supports (18). A slide closure (19) is provided to partially close or reduce the width of the cylinder opening so as to afford means for varying the duration of the exposure for any given speed of rotation of the shutter. This closure is held in place against the inner surface of the cylinder by means of retaining members engaging the flanges (20) of

the end members of the cylinder. The slide-
able closure carries a spring-pressed pin
(21) which is arranged to engage one of a
series of holes (22) formed in one of the
5 transverse edges of the opening of the cylin-
der to maintain the closure in adjusted pos-
ition. In practice these holes may be num-
bered or otherwise designated, so as to serve
as guides for the proper positioning of the
10 slideable closure to secure any desired length
of exposure.

To rotate the shutter I provide one end of
the cylinder with a toothed wheel (23)
which meshes with one of the train of gears
15 (24) and is driven by any suitable power,
such as an electric motor (25). The gears
(24) may be changed to change the speed of
rotation of the shutter so as to obtain a
greater variation in the duration of expo-
20 sure than is afforded by the slideable closure;
but it will be understood that these gears
may be dispensed with and the speed varia-
tions sought obtained by other means.

To control the starting and stopping of
25 the rotation of the shutter I provide a bell
crank (26), pivotally supported in a stand-
ard (27) and controlling, through a con-
necting rod (28), a knife switch (29) which
is arranged to make or break the electrical
30 connection of the motor. Normally, when
the shutter is at rest, the projection (30)
carried at the end of the vertical arm of the
bell crank is in engagement with the recess
(31) formed in the inner rim of the toothed
35 wheel, and the horizontal arm is raised by
the tension spring (32) to open the switch.
The recess (31) is located with reference to
the aperture in the shutter so that when the
shutter is in position of rest said aperture
40 will be below the plane of the overhanging
edges of the screens, thereby preventing the
light from penetrating the space above. To
depress the horizontal arm of the bell crank
so as to close the switch and lift the projec-
45 tion carried on the other arm clear of the
recess, I have a depressing rod (33) pivotally
suspended from a rocker arm (34) which is
actuated by a downward pressure of the
handle lever 5 upon the closing of the cover
50 of the printing frame. The rod has a lug
(35) near its lower end, which rests loosely
on a pin (36) carried on the horizontal arm
of the bell crank. It will be seen that when
the printing elements are in place in the
55 frame, the operation of shutting the cover
upon them will automatically start the rota-
tion of the shutter. As the shutter revolves,
the bell crank is maintained in position to
keep the switch closed by contact of its pro-
60 jection (30) with the inner rim of the
toothed wheel. A cam (37) carried on the
side of the toothed rim, slightly in advance
of the recess, is arranged to engage the bent
end (38) of the depressing rod to shift the
65 rod laterally so as to disengage its lug from

the pin (36) and hold it out of engagement
until the cover is raised. This serves to
prevent an involuntary second exposure of
the same sensitized elements. Upon the
completion of a revolution of the shutter,
70 the projection (30) again enters the recess
(31) and the horizontal arm is raised by the
spring (32) to open the switch and stop
the rotation thereof. When the cover is
raised to remove the print, the depressing
75 rod is released and is drawn upwardly by
the spring (39) and laterally by the spring
(40) toward the pin (36) and into engage-
ment therewith, thus setting the mechanism
for a subsequent operation.

In the foregoing specification I have de-
scribed what I believe to be the best mode
of applying my invention, but it will be
understood that the construction and ar-
rangement of the various parts may be
modified from that illustrated in the ac-
companying drawing without departing
from the spirit of my invention.

What I claim as my invention, and desire
to secure by Letters Patent, is:

1. In a photographic-printing apparatus,
the combination with a printing frame; of a
rotary shutter; a source of artificial actinic
light arranged in the interior of the shutter;
means for rotating the shutter; and means
actuated by the rotary movement of said
shutter for automatically stopping the rota-
tion thereof upon the completion of one
revolution.

2. In a photographic-printing apparatus,
the combination with a printing frame; of a
revoluble cylinder disposed relatively to the
frame, said cylinder having a longitudinal
aperture for the passage of light formed in
its periphery, and a slideable closure for
reducing the width of said aperture; a
vacuum arc light source inside the cylinder;
means for rotating the cylinder; and means
actuated by the rotary movement of said
cylinder for automatically stopping the
rotation thereof upon the completion of one
revolution.

3. In a photographic-printing apparatus,
the combination with a printing frame hav-
ing a movable cover; of a rotary shutter; a
vacuum arc light source arranged in the
interior of the shutter; means for starting
the rotation of the shutter, actuated by the
closing of the cover upon the frame; and
means for automatically stopping the rota-
tion on the completion of one revolution.

4. In a photographic-printing apparatus,
the combination with a printing frame of a
rotary shutter comprising a hollow opaque
cylinder having a section of its periphery
removed to form a longitudinal aperture,
and a slideable closure secured to said cylin-
der and adapted to reduce the width of said
aperture.

5. In a photographic-printing apparatus,

- a printing frame; a vacuum tube lamp disposed longitudinally below said frame; a pair of opaque screens disposed above said tube, approximately parallel thereto, and spaced apart to form an aperture for the passage of light; a rotary shutter arranged axially about the vacuum tube lamp, and adapted to close said aperture during a part of one revolution of said shutter; and means for rotating the shutter.
- 10 6. In a photographic-printing apparatus, a printing frame having a hinged cover; a rotary shutter; an electric motor for rotating the shutter; a switch for controlling the motor circuit; means for closing said switch, actuated by the closing of the cover upon the frame; and means for automatically opening the switch upon the completion of a revolution of the shutter.
- 15 7. In a photographic printing apparatus, a housing comprising a printing frame; a vacuum tube lamp arranged within the housing; an opaque partition between the lamp and the printing frame, said partition having an aperture for the passage of light; a rotary shutter disposed axially about said lamp and arranged to close the aperture in said partition during a predetermined part
- of a revolution of the shutter; and means for rotating the shutter.
8. In a photographic printing apparatus, a housing comprising a printing frame portion, having a hinged cover; a vacuum tube lamp arranged within the housing; an opaque partition between the lamp and the printing frame, said partition having an aperture for the passage of light; an adjustable rotary shutter disposed axially about the said lamp and arranged to close the aperture in said partition during a predetermined part of a revolution of the shutter; means for rotating the shutter; means for controlling the starting of said rotating means, actuated by the closing of the cover upon the frame; and means for automatically controlling the stopping of the rotation of said shutter upon the completion of one revolution thereof.
